UNITED STATES PATENT OFFICE.

ROBERT CHAMBERS NORMAN, OF MELBOURNE, VICTORIA.

DESIGN FOR A GAME-BOARD.

SPECIFICATION forming part of **Design No. 26,390**, dated **December 8, 1896**.

Application filed July 2, 1896. Serial No. 597,905. Term of patent 14 years.

To all whom it may concern:

Be it known that I, ROBERT CHAMBERS NORMAN, a subject of the Queen of Great Britain, residing at No. 58 Russell Street, 5 Melbourne, in the British Colony of Victoria, secretary and superintendent of the Alfred Hospital, Melbourne, aforesaid, have invented and produced a new and original Design for Game-Boards, of which the following is a 10 specification, reference being had to the accompanying drawings, forming part thereof.

Figure 1 is a plan view of a game-board, showing my design; and Fig. 2 is a cross-sectional view thereof.

15 This design consists in a board or apparatus for playing a new game.

The board is in shape approximately oval

or oblong with rounded ends, and its playing or upper surface A may be covered with cloth, after the manner of a billiard-table.

20 Transverse lines B and C are marked on the surface of the board near each end, and a short distance in front of the line C is disposed an upright D, about which is described a circle H. A net or reticulated border E is arranged continuously around the edge of the table.

I claim—

25 The design for a game-board substantially as herein shown and described.

ROBERT CHAMBERS NORMAN.
